UNITED STATES PATENT OFFICE.

LESLIE E. COON, OF CHATHAM, NEW JERSEY, ASSIGNOR TO WESTERN ELECTRIC COMPANY, INCORPORATED, OF NEW YORK, N. Y., A CORPORATION OF NEW YORK.

SELECTIVE SIGNALING SYSTEM.

1,250,804.

Specification of Letters Patent. Patented Dec. 18, 1917.

Application filed June 18, 1917. Serial No. 175,396.

To all whom it may concern:

Be it known that I, LESLIE E. COON, a citizen of the United States, residing at Chatham, in the county of Morris and State of New Jersey, have invented certain new and useful Improvements in Selective Signaling Systems, of which the following is a full, clear, concise, and exact description.

This invention relates to selective signaling systems and more particularly to selective signaling systems in which are employed selectively operated step-by-step circuit controlling devices adapted to be operated in response to current impulses of opposite polarity over a line circuit to close signaling circuit contacts. Such are shown and described in a co-pending application to Joseph C. Field, Serial No. 98,384, filed May 18, 1916.

20 A step-by-step device of the character which may be employed in this invention is disclosed in an application to Joseph C. Field, Serial No. 98,384, filed May 18, 1916, in which there is shown and described a 25 step-by-step circuit controlling device comprising a step-by-step element operated in response to current impulses of opposite polarity through a polarized stepping magnet to close station contacts controlling signaling 30 circuits. Provision is made whereby all step-by-step elements may be advanced to a predetermined position, in which position impulses impressed upon the line will cause an advancement of all step-by-step elements 35 to momentarily operate signaling devices.

The object of this invention in general is to provide means whereby an audible signal, such as a single stroke bell, may be operated at all stations simultaneously, and in consonance with impulses from an extraneous 40 source, such as time signals over a telegraph line.

In accordance with the general features of this invention there is provided a signal at 45 each station, the winding of which is adapted to be brought into circuit with the step-by-step element in its momentary closing position, to receive the discharge of a condenser connected in bridge of the line wires in series with the polarized stepping magnet. A second condenser included in series with the signal and in bridge of the first-mentioned condensers prevents a direct circuit path being established through the stepping magnet.

55 The drawing is a diagram of a circuit

and apparatus illustrating the features of this invention.

As shown in the drawing, 5 and 6 designate line wires which terminate in contacts 7, 8, 9 and 10 of a pole-changing relay 11, 60 the armature springs 12 and 13 of which are connected with a source of current 14. A circuit for the pole-changing relay 11 includes a battery 15, a key 16, by means of which the impulses are sent to operate the selective 65 circuit controlling device, and contacts 17 of a relay 18 which are adapted to be included in circuit with the relay 11 by means of a switch 19. The relay 18 may be connected with a telegraph circuit over which 70 time signals are sent. The above enumerated apparatus is located at a dispatcher's station designated as A.

Way-stations B and C are associated with the line wires 5 and 6 and at each of these 75 way-stations there is located a step-by-step circuit controlling device comprising in general a step-by-step rotatable element 20 to which is secured a toothed wheel 21. A pivotally supported pawl 22 is carried by a pivoted arm 23 which is swung in the same direction in response to each alternate movement of an armature 24 of a polarized stepping magnet 25. A contact arm 26 carried by the step-by-step element 20 is adapted to 80 be carried in the movement of said step-by-step element 20 into successive engagement with stationary contacts 27, 28, 29 and 30. When the contact arm 26 is in engagement with the contacts 27 or 28, and the stepping 85 magnet 25 is deenergized, a contact spring 31 controlled by the pivoted arm 23 is moved into engagement with a pin 33 or 34, as the case may be, to retain the step-by-step element 20 in its advanced position and maintain the contact arm 26 in engagement with one of the contacts 27 or 28. In the case of 90 the contact 28 this completes a local circuit through a signal 35. When the step-by-step element 20 is advanced to a position where 100 the contact 26 is in engagement with the contact 29, said step-by-step element will be held through the engagement of contact spring 31 with a hooked holding member 37 carried by the step-by-step element 20. With 105 the parts in this position a single impulse through the stepping magnet 25 will advance the contact arm 26 into engagement with the contact 30 where it will be held only so long as there is energy through the step- 110

ping magnet 25. As soon however as the stepping magnet is deenergized, the step-by-step element will drop back and the arm 31 will reengage the hooked member 37 to maintain the step-by-step element in its advanced position. With this arrangement the contact arm 26 may be moved into temporary engagement with the contact 30 as many times as desired, through energization and deenergization of the stepping magnet 25 without starting the step-by-step element 20 from a zero position each time.

The stepping magnet 25 is connected in bridge of the line wires 5 and 6 and in series with a condenser 40. A bell 41, arranged to give a single stroke signal in response to each impulse of current therethrough, has one end of its winding connected with the contact 30 and its other end with one plate of a condenser 42, the other plate of which is connected between the line wire 5 and the condenser 40.

In the operation of this invention all of the selectors on the line will be operated to move their step-by-step elements into a position where the contact spring 31 is in engagement with the hooked member 37. Then, upon closure of the switch 19, the pole-changer magnet 11 will be operated in consonance with the impulses through the relay 18, to send current impulses over the line wires and through the stepping magnet 25 at each station. During the energization of the stepping magnet in response to these impulses, the contact arm 26 engages the contact 30 but becomes disengaged therefrom upon the deenergization of the stepping magnet. Each time the contact arm 26 and the contact 30 are brought into engagement the condenser 40 discharges through the winding of the bell 41 to cause a one-stroke signal thereof.

Two signals on the bell 41 will be given for each impulse through the relay 18. The condenser 42 prevents a direct current path being established through the selector bridge, thereby preventing the selector sticking in operated position, due to energy through its winding.

50. What is claimed is:

1. In a selective signaling system, a pair of line wires, a sending station and a plurality of way-stations connected therewith, a step-by-step circuit controlling element located at each of said way-stations, a stepping magnet at each of said way-stations for controlling the advancement of the step-by-step element thereat, a contact adapted to be closed and maintained closed in one

position of said step-by-step element, a signal, a circuit therefor closed by said contact, a second contact adapted to be intermittently closed by said step-by-step element in a second position thereof, and in response to the energization and deenergization of said stepping magnet, a signal, and means for causing said signal to give a single stroke indication for each closure of said second mentioned contact.

2. In a selective signaling system, a pair of line wires, a sending station and a plurality of way-stations connected therewith, a step-by-step circuit controlling device located at each of said way-stations, a stepping magnet at each of said way-stations connected in bridge of said line wires and adapted to control the advancement of the step-by-step element thereat, a condenser included in series with each stepping magnet, a contact adapted to be closed and maintained closed by said step-by-step element in one position thereof, a signaling circuit controlled by the closure of said contact, a second contact adapted to be intermittently closed by said element in a second position thereof, and in response to the energization and deenergization of said stepping magnet, a signal, and means for causing said condenser to discharge through said signal at each closure of said second mentioned contact to cause said signal to give a one-stroke indication.

3. In a selective signaling system, a pair of line wires, a sending station and a plurality of way-stations connected therewith, a step-by-step circuit controlling device located at each of said way-stations, a stepping magnet at each of said way-stations connected in bridge of said line wires and adapted to control the advancement of the step-by-step element thereat in response to current impulses of opposite polarities over the line wires, a condenser included in series with each stepping magnet, a contact adapted to be closed and maintained closed by said step-by-step element in one position thereof, a signaling circuit controlled by the closure of said contact, a second contact adapted to be intermittently closed by said step-by-step element in a second position thereof and in response to the energization and deenergization of said stepping magnet, a signal connected in bridge of said condenser to be operated by the discharge thereof, and a second condenser in series with said signal.

In witness whereof, I hereunto subscribe my name this 12th day of June, A. D. 1917.

LESLIE E. COON.
